INTERLOCKING SYSTEM FOR RAILROADS

Frank Benedict, Rutherford, N. J., assignor to
General Railway Signal Company, Rochester,
N. Y.

Application July 30, 1936, Serial No. 93,432

6 Claims. (Cl. 246—134)

This invention relates to centralized traffic controlling systems for railroads and more particularly pertains to means for indicating to the operator in a central office the route, and direction of travel thereover, manually initiated by the operator.

The present invention relates to improvements in the indications provided in a system of the so-called entrance-exit route type interlocking system disclosed in the prior patent of S. N. Wight, Patent No. 2,121,846 dated June 28, 1938, and is also an improvement over the indication system disclosed in the prior application of Forest B. Hitchcock, Ser. No. 74,709 filed April 16, 1936.

15 The organization of a system embodying the present invention contemplates a miniature track diagram located in the central office which corresponds with the actual track layout in the field. An entrance button is located on the diagram at each route determining point on the track layout and an exit push button and also an exit indicator is located at each point to which traffic may go. That is, for each signal location there is an entrance button which button requires the operation of an exit push button at the 20 end of the proposed route in order to establish movement of traffic over a particular trackway route.

One of the objects of the present invention is 30 to show by means of indications on the miniature track diagram the route which has been initiated by the operator and the route that will be established in the field including the direction in which trains may move thereover when established, and to accomplish this in a simple and direct manner.

Other objects, purposes and characteristic features of the present invention will be in part obvious from the accompanying drawing and in 40 part pointed out as the description of the invention progresses.

In describing the invention in detail reference will be made to the accompanying drawing which 45 illustrates a control panel constructed in accordance with the present invention as it appears under normal conditions when no route or routes have been set up, and which drawing also illustrates the track layout in the field which corresponds with the miniature track diagram.

50 For the purpose of further simplifying the illustration and facilitating in the explanation thereof various parts and circuits constituting the embodiment of the invention have been shown diagrammatically, and certain convention illustrations have been employed, the drawing hav-

ing been made with the idea of making clear the purposes and principles of the invention together with the mode of operation rather than with the idea of construction and arrangement of parts that would probably be employed in practice. 5 In practicing the invention it may be applied to track layouts on which a plurality of routes may be simultaneously established and in which a plurality of track switches and cross-overs are included in the same route and controlled by the 10 same entrance and exit control buttons. The various relays and their contacts are illustrated in a conventional manner and symbols are employed to indicate connections to the terminal of batteries and other suitable sources of electric 15 current supply instead of showing all the wiring connections to such terminals.

Symbols (+) and (—) are employed to indicate the positive and negative terminals respectively of suitable batteries or other sources of electric 20 energy; and those terminals with which these symbols are used are presumed to have current flowing from the positive terminal designated (+) to the negative terminal designated (—). The symbols (B+) and (B—) are employed to 25 indicate the positive and negative terminals respectively of a suitable battery having a mid-tap (CN).

Symbols employed with any one circuit are considered to designate a single source of energy in 30 this embodiment of the present invention but as many sources may be provided as found necessary or expedient in the practice of the invention.

APPARATUS IN GENERAL

In the accompanying drawing the invention has been shown applied to a track layout B consisting of a section of main line track 5 and a turnout track 6 connected by the switch TS, which switch is operated by the switch machine SM which may be of any suitable type. However, it should be understood that the invention is not limited as shown to the control of a single switch but may be applied to any track layout found in practice. 45

Signal 2 provides for governing east-bound traffic over the main track 5, and signal 2^d governs traffic over the switch TS onto the turnout track 6. Signal 3 provides for governing west-bound traffic over the main track 5 and signal 4 provides for governing west-bound traffic off of the diverging track. 50

In the central office is located a control panel A comprising a miniature track layout having indication lamps and control buttons thereon, 55

as shown on the drawing. This panel is preferably made of a dark colored material upon which is formed by grooves of other suitable means, markings to represent a track layout, 5 which track layout corresponds to the actual track layout B in the field. The base of these grooves, when employed, should be marked by a distinctive color such as white to make these grooves stand out from the dark background.

10 Located on the control panel are suitable buttons and indicators including the entrance buttons 2NB, 3NB and 4NB which are located at points corresponding to their respective signals as indicated by the prefix number. Located at 15 the center of these entrance buttons are suitable fixed indicators 2NBL, 3NBL and 4NBL, which have arrows located on their lenses which show the direction in which the corresponding signal in the field governs traffic. The arrows are 20 illuminated by lamps located underneath the lenses, which lamps have for convenience been shown displaced from the lenses in the drawing. The outer movable part of the button has located thereon a pointer 1 which is shown in its normal 25 position and may be rotated to correspond with the position of the arrow on the lens in the center of the button.

Adjacent to the entrance buttons are the exit indicators 2XL, 3XL and 4XL and the exit push 30 buttons 2XPB, 3XPB and 4XPB. The exit indicators are fixed indicators including lamps which when illuminated light the arrow located 35 thereon to show the proposed direction of the movement of traffic over the selected route. The exit push buttons XPB are of the self-restoring type and when actuated in conjunction with the corresponding entrance button closes a circuit for the control of route relays as shown in the drawing.

40 Associated with the entrance and exit buttons and the exit indicators are suitable route relays 2-3 and 2-4 of the polar neutral type. The operation of these route relays 2-3 and 2-4 effect the control of the switch TS through the switch 45 control relay Z which is a relay of the polar neutral type and preferably located in the central office.

In the accompanying drawing the entrance buttons are all shown in their normal no-route or 50 signal-at-stop position, while the polar contacts of the associated route relays are shown in their right hand positions, signifying that east bound traffic will be set up when these relays are energized.

55 OPERATION

Setting up a route.—Let us assume an operator wishes to set up a route over switch TS from signal 2 to signal 4 shown in the track layout B. In 60 order to do this he rotates the entrance button 2NB in a clockwise direction until the pointer 1 on the outer portion of the button corresponds to the position of the arrow on the stationary indicator 2NBL and completes the operation by pressing the 65 exit push button 4XPB.

On the completion of this sequence of operation of these control buttons the route relay 2-4 will become energized and the route that will be set up in the field will be indicated immediately to the 70 operator by the illumination of the exit indicator 4XL and the indicating lamp 2NBL in the center of the entrance button 2NB.

The circuit for the energization of the relay 2-4 is closed from (+) through the contact 10 of the 75 entrance button 2NB in the position shown by the

dotted line through the coils of the route relay 2-4, back contact 11 of relay 2-3, contact 12 of entrance push button 4NB in its normal position, contact 13 of the push button 4XPB in its depressed position to (-). The current which flows 5 in this circuit actuates or holds the polar contacts of the relay 2-4 to the right hand position as shown and picks up its neutral contacts, so that a stick circuit is established from (-) through front contact 14 and polar contact 15 of route 10 relay 2-4 in a right hand position to shunt out contact 13 of the exit push button 4XPB, which contact 13 is only closed momentarily as it is a self-restoring push button.

When the route relay 2-4 is energized, or 15 picked up, energy is supplied to the entrance indicator 2NBL located in the center of the entrance button 2NB, and the exit indicator 4XL through a circuit from (+) through front contact 16 of the route relay 2-4, and the polar contact 17 of the 20 route relay 2-4 in the right hand position through the indicator lamps 4XL and 2NBL in series to the terminal (-) of the same source of current.

With the neutral contacts of route relay 2-4 25 picked up, the pick-up circuit for the 2-3 route relay is opened at back contact 18 and therefore no other route can be established until the route relay 2-4 is deenergized. This may be done by restoring the entrance button 2NB to its normal 30 position.

Similar circuits as the circuit traced for the indicating lamps 2NBL and 4XL traced above are provided for the remaining indicating lamps. For instance, one of these indicating circuits is 35 controlled through front contact 16 and polar contact 17 to the left of the route relay 2-4, a second circuit is closed through the neutral contact 19 and the polar contact 20 to the right of the route relay 2-3 and another circuit for indicating 40 lamps may be traced through the front contact 19 of the route relay 2-3 and the polar contact 20 thereof assuming the left-hand position. Since these route relays 2-3 and 2-4 are electrically 45 interlocked through their respective back contacts 11 and 18, only one of these route relays may be energized at one time. Also, since the polar contacts of these relays may assume one extreme position at one time only, an interlock is provided between lamps indicating east-bound traffic and 50 lamps indicating west-bound traffic over the same route.

The switch machine SM operates the switch TS to either of its two positions through the medium of the relay Z which relay in turn is controlled by 55 the route relay 2-4 or 2-3 as the case may be. With the route relay 2-4 now energized toward the right, for reasons above given, an energizing circuit for the switch control relay Z is closed, which may be traced from (B-) through the front contact 21 of the route relay 2-4 through the coils of relay Z to terminal (CN) which constitutes a mid-point of the same source of current.

The signal 2^d governing the route over the switch TS to signal 4 is also controlled by the 60 route relay 2-4. The circuit for clearing this signal 2^d may be traced from (+) through neutral contact 22 of route relay 2-4, through polar contact 23 of route relay 2-4 in the right hand position through signal 2^d to (-).

The signals 2, 2^d, 3, and 4 shown in the track layout B are preferably light signals of the three indication type and the indications displayed thereby will depend on the condition of traffic ahead of the signal, the position assumed by the 75

track switch and the fact that the switch and the control relay Z for controlling the same assume corresponding positions. Reference number 8 has been used in the track layout B to show the signal control wires in the field, such for instance as shown by dot-and-dash lines in Fig. 3B of the prior patent of S. N. Wight, Patent No. 2,082,436 dated June 1, 1937, controlled in this manner. Any suitable type of signal such as a semaphore signal, a searchlight of a movable spectacle type light signal may be used in practicing the invention without departing from the scope of the invention.

It is believed that it will be readily understood by analogy to the above description, how a route may be set up from signal 2 to signal 3 or in the reverse directions from signal 3 to signal 2, and from signal 4 to signal 2. However, when a route is set up from signal 4 to signal 2 or from signal 3 to signal 2 the route relay 2-4 or 2-3, as the case may be, is energized so that its polar contacts are moved to the left hand position. To set up a route from signal 3 to signal 2 the entrance button 3NB is turned to its left hand position and the exit 25 push button 2XPB pressed. This energizes the relay 2-3 so its polar contacts move to their left hand position through a circuit from (+) through contact 9 of entrance button 3NB in its dotted line position, coils of relay 2-3 through back contact 18 of relay 2-4 through contact 10 of entrance button 2NB in its normal position through contact 24 of the exit push button 2XPB in its depressed position to (-). When the neutral contacts of relay 2-3 are picked up a stick 30 circuit is closed which includes the front contact 25 and polar contact 26 positioned to the left of relay 2-3 to shunt out the contact 24 of the push button 2XPB which is of the self-restoring type.

The operation of the entrance button for the beginning of a route and the operation of the exit push button for the end of the corresponding route in the proper sequence will energize one of the route relays 2-4 or 2-3 with current of one polarity or the other depending on the particular route and the direction of traffic over the particular route to be established. After the completion of this operation the indicator in the entrance button and exit indicator located near the exit button will become illuminated, showing the extremities of the route and the direction of traffic over the route that will be established in the field. That is, if a route from signal 2 to signal 3 is set up indicators 2NBL and 3XL will light up. Likewise a route from signal 4 to signal 2 would be indicated by the entrance button 4NB and the exit indicator 2XL being lighted. Also, a route from signal 3 to signal 2 would be indicated by lighting of the entrance button 3NB and the exit indicator 2XL.

It will also be noted that the control of the switch and the signals for the route selected will be effected directly by the route relay involved, which relay has been properly positioned by the manipulation of the associated entrance and exit buttons. For instance signal 3 is cleared by a circuit from (+) through the front contact 27 and the polar contact 28 to the left of route relay 2-3 through signal 3 to (-).

When route relay 2-3 is energized the switch control relay 2 is positioned so that the switch TS is operated to its normal position. The circuit which controls the relay Z to that polar position may be traced from (B+) through contact 29 of route relay 2-3 through the coils of the relay Z to common return wire (CN).

Instead of having the arrows embossed on a stationary lens of the entrance buttons 2NBL, 3NBL and 4NBL as shown in the drawing, these lenses may be movable in the rotatable position of corresponding entrance buttons. If this modified construction is employed, the arrow would preferably point upward when this button assumes its normal no-route position. The arrow could in this modified construction not be lighted while the arrow is pointing upwardly. In this form of construction the pointer 7 would preferably be omitted since the dark or lighted arrow by its position would show the position assumed by the arrow.

Summary

15

The present invention provides a miniature track diagram with its associated entrance and exit buttons and entrance and exit indicators of an NX interlocking system in such a way as to show immediately the extremities of the route attempted to be set up and the direction of traffic over this route. This is believed to be desirable so that the operator can readily ascertain the extent of the route set up and thereby eliminate the tendency to set up a conflicting route or disturb a route already set up.

Having thus shown and described a centralized traffic controlling system for railroads, as including one specific embodiment of the indication system constituting the present invention, it is desired to be understood that various modifications, alterations or adaptations may be employed to meet the requirements encountered in practicing the invention, and without in any manner departing from the spirit or scope of the invention, except as demanded by the scope of the following claims.

What I claim is:

1. In an interlocking system of the entrance-exit type, the combination with a track layout in the field including a plurality of conflicting routes and a corresponding miniature track layout on a panel in the control office, manually operable means at each end of each route on said miniature track layout, an indicating lamp associated with each of said manually operable means, a route relay for each route, means effective upon operation of manually operable means at the entrance end and at the exit end of a particular route from normal for energizing a route relay identifying that route, means controlled by said route relay for setting up a corresponding route on the actual track layout, and a contact on said route relay for energizing the indicating lamps at the entrance and exit ends of the route corresponding to said route relay.

2. In an interlocking system of the type described, the combination with an actual track layout in the field including a plurality of conflicting routes, a panel in the control office having a miniature track layout depicted thereon, manually operable means at each end of each route of said miniature track layout, a route relay for each route, an energizing circuit for a particular route relay energized by current of one polarity if the manually operable means for that route are operated in a predetermined order and for energizing said relay by current of the reverse polarity if said manually operable means are operated in the reverse order, means for setting up traffic in one direction over the corresponding route in the field when said relay is energized by current of one polarity and for setting up traffic in the opposite direction over the same route when said relay is energized by cur-

- rent of the opposite polarity, and means controlled by said relay for indicating on said miniature track layout the particular relay which has been energized and also indicating with what polarity of current said relay has been energized.
5. 3. Control apparatus for interlocking systems comprising, a control panel having a miniature track layout depicted thereon, manually operable means at each end of each route on said miniature track layout, an entrance indicating lamp associated with each manually operable means, an exit indicating lamp associated with each manually operable means, a route relay for each route on said miniature track layout for setting up a corresponding route on an actual track layout and energized only if the manually operable means at the ends of the corresponding route on the miniature track layout are operated from normal, composite energizing circuits for said lamps each composite circuit including the lamp at the common entrance to a plurality of routes included in series with lamps at the exit ends of these routes connected in multiple, and means for controlling said composite energizing circuits for said route relays.
10. 4. In a switch and signal control system for railroads; a track layout having a plurality of different routes with power operated means for setting up the different routes and with signals at the entrance and exit ends of such routes for governing traffic thereover, a control panel having a miniature track diagram of said track layout, manually operable devices on said miniature track diagram at points corresponding to the locations of said signals, indicator means associated with each manually operable device at points corresponding to said signal locations, route establishing means responsive only to the joint operation of said manually operable devices for the entrance and exit ends alone of any given route to control said power operated means to set up that route and clear the signal at the entrance thereto, and circuit means controlled only upon the response of said route establishing means, irrespective of the response of said power operated means, to effect the energization of said indicator means for the entrance and exit ends of any given route being set up by said route establishing means.
15. 5. In a switch and signal control system for railroads; a track layout having a plurality of different routes with power operated means for setting up the different routes and signals for governing traffic over such routes; a control panel having a miniature track diagram of said track layout; manually operable devices on said miniature track diagram at points corresponding to the locations of the signals in the actual track layout,

each of said manually operable devices being operable to designate its location as an entrance point or as an exit point; indicator means associated with each of said manually operable devices for indicating when illuminated whether the corresponding signal location is an entrance point or an exit point; route establishing means responsive to the joint operation of said manually operable devices at the opposite ends only of any given route when such devices are operated to 10 designate one end as an entrance point and the other end as an exit point with such response of said route establishing means effecting the control of said power operated means to set up the designated route through the actual track layout and 15 clear the signal at the designated entrance end; and circuit means controlled by said route establishing means only after the response of such route establishing means to the joint operation of said manually operable devices to effect the selective energization of said indicator means for the entrance end and the exit end of the route being 20 set up to distinctively designate the entrance and exit ends of that route.

6. In an interlocking system of the entrance-exit type, a track layout having different routes set by power operated means with signals at the entrance to such routes for governing traffic thereover, a control panel having a miniature track diagram corresponding to said track layout, 25 manually operable devices on said miniature track diagram at points corresponding to the locations of said signals in said track layout and constituting the entrance and exit ends of the different routes, two indicator lamps associated with each 30 of said manually operable devices, one of said lamps being provided with an arrow index to show the direction of traffic governed by the signal for the corresponding location and the other of said lamps being provided with an arrow index to show 35 the opposite direction of traffic, route establishing means responsive to the joint operation of said manually operable devices for the entrance and exit ends alone for any given route to control said power operated means to set up that route and 40 clear the signal at the entrance thereto, and circuit means rendered effective only after the response of said route establishing means and selectively controlled thereby to energize the indicator lamps at the opposite ends of any given 45 route being set up by said route establishing means, said circuit means energizing the lamps having arrow indices for the same direction of traffic and corresponding to the direction of traffic governed by the signal cleared at the entrance to 50 such route.
